UNITED STATES PATENT OFFICE.

CHARLES Y. KNIGHT, OF OAK PARK, ILLINOIS, ASSIGNOR OF ONE-HALF TO LYMAN BERNARD KILBOURNE, OF CHICAGO, ILLINOIS.

INTERNAL-COMBUSTION ENGINE.

968,166.

Specification of Letters Patent. Patented Aug. 23, 1910.

Application filed April 4, 1904. Serial No. 201,447.

To all whom it may concern:

Be it known that I, CHARLES Y. KNIGHT, a citizen of the United States, residing at Oak Park, in the county of Cook and State of Illinois, have invented certain new and useful Improvements in Internal-Combustion Engines, of which the following is a full, clear, and exact specification.

My invention relates to internal combustion engines and it has for its primary object to provide an improved form of such engine in which the moving parts for controlling the fluid contents of the explosion space during the high pressure strokes of the piston shall be positively acting and the use of puppet valves or the like for such purpose avoided.

With these ends in view, the invention consists in certain features of novelty in the construction, combination and arrangement of parts by which the said object and certain other objects which will hereinafter appear are attained, an example of which invention will now be described with reference to the accompanying drawings, the invention being more particularly pointed out in the claims.

In the said drawings—Figure 1 is a vertical sectional view of an engine or motor embodying this invention. Fig. 2 is a similar section taken on a plane at right angles to that of Fig. 1. Fig. 3 is a side elevation thereof partly broken away and partly sectioned. Fig. 4 is a plan view. Fig. 5 is a plan section on the line 5—5, Fig. 1. Fig. 6 is a section taken through the base longitudinally of the crank shaft, and Fig. 7 is an enlarged detail plan section taken approximately on the line 7—7, Fig. 1.

In carrying out my invention, I employ telescoped or concentric cylinders or cylindrical elements, the outer one of which is fixed, while the inner one moves or reciprocates with relation thereto. Concentric with the inner cylindrical element, I employ a third cylindrical element or member, which, in conjunction with the said movable element, serves to control fluid exhaust from the explosion space of the engine and confine the explosion to the piston, the explosion space and piston being surrounded by the said movable element, and with relation to which the piston reciprocates coaxially and is connected therewith for imparting movement thereto relatively to the fixed cylin-

der and to the said third cylindrical element. The fixed cylinder has ports which at times communicate with the explosion space, and at other times are cut off therefrom by port-controlling provisions, or means external to the explosion space and reciprocating cylinder but moving in concert with the latter in co-operative relation to the inner face of the fixed cylinder. I will describe in detail the example of my invention shown in the drawings embodying these principles.

The inner reciprocating element is shown at 1, and it is in the form of an open-ended barrel, and 14 is the fixed cylindrical element, while 2 is the third cylindrical element which, in this example, is fixed against movement with the piston 3 by being rigidly secured to the fixed cylinder or cylindrical element 14 and projects into the latter and is spaced from the walls thereof and also projects into the cylindrical element 1 in a position opposed to the piston 3, the element 2 in the example shown being in the form of a head or extension on the fixed cylinder head and all of these parts being co-axial with the piston, with the reciprocating cylindrical element 1 situated in the annular space between the opposed faces of the fixed cylinder and the head 2 and moves with relation to but in concert with the piston for co-operating with the head 2 to control the fluid contents of the explosion space during the compression and explosion strokes which are the high pressure strokes of the piston and while the element 1 moves contemporaneously with the piston it moves a shorter distance and undergoes a less number of strokes than the piston. The piston and the reciprocating element 1 are timed in their movements in accordance with the four-stroke cycle of an explosion motor so as to draw in, compress and explode the charge between and against the head 2 and the piston and then exhaust the spent gases from the explosion space. The piston 3 is connected by a pitman 4, or other suitable means, with crank 5 of a crank shaft 6.

The air or other ingredients of the explosive charge may be admitted to the explosion or firing space within the element 1 and between the head 2 and piston 3 through the wall of the outer cylinder 14 and the parts above described are so constructed, combined and timed in their action that the motion of the piston results in a

complementary motion of the inner cylindrical element or cylinder 1 and its associated parts, presently to be described, not only for controlling the fluid contents of the explosion space during the high pressure strokes as before mentioned, but for controlling also the ports of the fixed cylinder during the inspiration and exhaust strokes.

A zone of the cylinder 1 or a portion of its wall area at or near the explosion end or end adjacent the igniting means is apertured or provided with ports preferably on opposite sides, one an intake port 11 and the other an exhaust port 12, and at a point below or farther outward than the port 12 it is provided with a second exhaust port 13 ordinarily known as a terminal exhaust port, which in this example of the invention is the main exhaust port and which during the inspiration, compression and firing strokes is cut off by the piston 3 while the exhaust port 12 and intake port 11 are closed at the proper periods by the wall of cylinder 14 and the lower or inner end of the head 2 over which the cylinder 1 reciprocates in sliding contact for lapping its apertured zone or port area with the head 2. On cylinder 14 is formed an outlet connection 15 for the exhaust port 12 and an intake connection 16 for the intake port 11, the connection 16 being arranged considerably below the exhaust connection 15, and the inner end of the head 2 being provided with an exhaust passage 18 substantially opposite the exhaust port or connection 15, so that when the cylinder 1 descends to connect the intake 11 with the intake connection or port 16, the exhaust port 12 although being also below or uncovered by the head 2 at that time, is nevertheless closed at its outer end by cylinder 14. It is also seen that around the cylinder 1 where the two ports 11, 12 are situated, is disposed an annular element 19 through which said ports are formed and in which, on both sides of said ports, are situated suitable piston rings 20 which fit closely against the cylinder 14, thereby constituting port-controlling provisions or means external to or concentric with the explosion space and cylinder 1, coöperating directly with the inner face of fixed cylinder 14 and moving in concert with cylinder 1 and the piston for cutting off communication with the explosion space through the exhaust port of the fixed cylinder during the inspiration stroke, and through the intake port during the exhaust stroke (and by the expression "external to" as employed herein with reference to the port-controlling provisions last referred to and the cylinder 1, I wish to be understood as meaning port-controlling means disposed without and not within the cavity of said cylinder.) When the inspiration outward stroke is finished, 65 or about finished, the cylinder 1 rises a suffi-

cient distance to cover the inlet port 11, or to take it out of register with the fixed port 16, but does not rise far enough to bring the exhaust port 12 into register with exhaust passage 18 and exhaust port or outlet 15 70 until the charge thus sucked into cylinder 1 has been compressed by the succeeding inward stroke of the piston and has been exploded, and the second inward stroke of the four-stroke cycle, that is, the exhaust 75 stroke, is commenced.

Near the conclusion of the working or firing stroke, the piston uncovers terminal exhaust port 13, allowing the major portion of the exhaust to escape, and subsequently 80 the cylinder 1 moves to place the other exhaust port 12 into communication with fixed exhaust port 15 and passage 18 so that the return movement of the piston will force the remaining smoke and products of combustion out through passage 18 and ports, 85 12, 15. If desired, this upward movement of the cylinder 1 may also be utilized for the purpose of compressing a quantity of fresh air in a cylinder or chamber 21 formed in 90 the upper end of cylinder 14 above the element 19, which latter serves as a plunger or annular piston for crowding such air into chamber 21; and the air thus compressed is admitted to cylinder 1 after the 95 piston 3 has passed the main exhaust port 13 on its return stroke. This admission of air to the interior of the explosion space or chamber may be accomplished in any suitable way. For example, one side of chamber 21 is formed with a by-pass 22 so that when the intake port 11 reaches said by-pass 100 the air compressed in chamber 21 will pass around the upper part of the element 19 and enter the explosion chamber through a 105 port or passage 23 formed in the head 21 and preferably turned downwardly at its inner end so that the air current will descend into the cylinder 1 on one side until it strikes the piston 3, which will cause it to ascend on 110 the other side toward the outlet passage 18, thereby crowding the remaining smoke through the exhaust port 15 and clearing out even the small percentage of the products of combustion that might have lingered in 115 the explosion space above the limit of the travel of the piston 3. Chamber 21 is supplied with air when cylinder 1 descends again through a small inlet port 24 which is opened and closed by the element 19. 120

The piston 3 being at or about the limit of its return or exhaust stroke, and starting, or about to start, downwardly on its inspiration stroke, the cylinder 1 is again moved downwardly to bring the intake port 11 into 125 register with the port or connection 16 and to close the ports or passages 15, 18, and the port 11 remains in register with the inlet connection or port 16 until the inspiration stroke is completed, whereupon cylinder 1 130

again rises to close inlet port 11 as before described. These movements of the cylinder 1 may be accomplished by a suitable operative connection with the piston, such 5 as will be presently described.

Interposed between the telescoped elements 1, 2, is a port-controlling means in the form of a packing of sufficient single width to remain lapped with the apertured 10 zone or port area of that one of the two elements 1, 2, in which the movable intake port 11 and exhaust port 12 are formed at the explosion end thereof, during the compression and explosion strokes, that is to say, substantially throughout one revolution 15 of the crank shaft notwithstanding the fact that the element 1 moves contemporaneously with the piston during such period. Consequently the ports of the explosion space are 20 tightly closed during these two high pressure strokes and possibility of leakage is reduced to the minimum. To this end the lower end of the head 2, in its cylindrical face, where it covers the ports 11, 12, is provided with a packing 25 which may be continuous or sectional, as desired. The pressure being always outward it is immaterial which way it is made. At suitable intervals 25 above the ports or passages 18, 23, the head 30 is provided with one or more packing rings 26 which prevent pressure from escaping over the upper end of cylinder 1 around which the cylinder 14 is contracted, as shown at 14'; for the purpose of obtaining 35 the desired compression in the air chamber 21 by the upward movement of the element 19. This element 19, however, as before mentioned, performs important functions in the control of the fixed intake and exhaust 40 ports 15, 16 at times when the explosion space within cylinder 1 is open, by reason of the ports 11, 12 thereof being out of lap with or uncovered by the port-controlling portion of the head 2, which occurs when 45 either of these two ports is below the head, and also when port 12 rises to the place where the head is cut away to form the passage 18, and at which time port 11 is in register with port 23. When ports 11, 12 50 are below the head, the element 19 intercepts communication between the exhaust port 15 and the explosion space via the exhaust port 12 of cylinder 1, and when ports 11, 12 are in register with ports 23, 18 respectively, said element 19 prevents the fire from the explosion space reaching the intake port 16 via port 23, and also prevents the fire and burned gases from passing around cylinder 1 in chamber 21 and entering the intake port 16, the piston rings 20 being a valuable auxiliary to the attainment of these desirable results, as well as 55 making the element or annular piston 19 sufficiently tight to produce the required air pressure in chamber 21.

The cylinder 1, if desired, may be exposed throughout as much of its surface as possible, without leaving the ports 11, 12 uncovered, when at the limit of its downward stroke, and the surface of cylinder 1 may be provided with radiating ribs or fins 27, adapted, if desired, to pass upwardly into the outer cylinder 14 as cylinder 1 rises, and to become exposed to the atmosphere when cylinder 1 descends, and by thus vibrating in the open air, cause the heat to radiate from cylinder 1 more rapidly.

In order that the main exhaust taking place through the exhaust port 13 may be conducted away, an exhaust connection 28 80 may be employed. This connection 28 is provided with a valve seat 29 arranged close to the line of movement of a boss 30 in which the exhaust port 13 is formed, so that while the port is in register with the connection 28, 85 the exhaust will not be allowed to escape excepting through said connection. In order that this connection 28 and the seat 29 may cover but the minimum amount of the surface of the cylinder 1, so as not to interfere 90 with the cooling of said cylinder, said connection and valve seat are formed on or secured to a ring 31 which surrounds cylinder 1 and is supported by standards 6, 7, 8, the latter being formed with shoulders 32 upon 95 which the ring 31 is held by nuts 33. These standards also pass through and are secured to ears 19 on head 2, and thus serve as supports for cylinder 14. The base flange 9 is preferably formed with a guide collar 34 100 which receives and steadies the lower end of cylinder 1 and forms in effect a continuation of cylinder 14 and makes an appropriate connection between cylinder 1 and crank case 35, in which latter the crank shaft 5 is 105 journaled in any suitable way.

The outer cylinder 14 of the engine thus described corresponds to what is the usual fixed cylinder in an ordinary explosion engine, but for the sake of exposing the sides 110 of the inner cylinder 1 to the cooling action of the atmosphere, the outer cylinder 14 is cut away near its lower end and supported by the standards 6, 7, 8 instead of being continuous with its base portion 34.

The head 2, if desired, may be formed with a water space 36 which may be provided with inlet and outlet connections 37, 38, and the inner end of the head may be made concave, as shown in Fig. 1 and 2, 120 and through the upper end of this concavity may be introduced a suitable igniter, here shown as a spark plug 39, whereby the explosive charge is ignited between the head and the piston. The head is formed with a 125 recess 40 for receiving this plug, and the recess is completely surrounded by the water space 36 for keeping the plug cool.

A suitable mechanism for operatively connecting the movable cylindrical element 1 130

with the piston 3 and imparting to said cylindrical element the before described movements will now be explained, it being understood, however, that this is but an example 5 of an appropriate mechanical movement or mechanism for accomplishing said result.

The cylinder 1 is connected to one end of a rod 41 by means of any suitable pivot 42 and a lug 43 secured to the cylinder or 10 formed thereon, and the other end of this rod 41 preferably passes into the crank case 35 and carries an eccentric strap 44 in which is journaled an eccentric 45 secured to one end of a pitman 46 whose other end is connected by a wrist-pin 47 with a gear wheel 48 journaled on shaft 49 in the crank case and deriving motion from a pinion 50 on the crank shaft 6, said gear and pinion being in 15 the proportion of two to one since the engine 20 is a four cycle type. The connection between the eccentric 45 and the pitman 46 may be accomplished in any suitable way. As shown in Fig. 7, it is effected by providing the pitman with two branches 51 secured 25 to the eccentric at one point by a transverse bolt 52 and at another point by a pivot pin 53 so that the rocking of the pitman 46 will also rock the eccentric in the strap 44 and will cause the rod 41 to rise and fall since 30 the pivot 53 is eccentric to the eccentric, and in fact is the shaft of said eccentric, but the ends of this pivot or shaft 53 are rigidly secured in two slides 54, 55 and these are 35 mounted upon two guide-ways 56, 57 respectively, which are connected together at one end by a cross-connection 58, and these guide-ways 56, 57 are provided with trunnions 59, 60, respectively, journaled in suitable standards 61, 62 rising from the bottom of the 40 crank case 35, so that as the main gear wheel 48 revolves, the eccentric will be rocked on its pivot 53 and also pulled back and forth bodily along the guide-ways 56, 57, while these guide-ways are also oscillated in a vertical direction by two cranks 61, 62, on a 45 crank shaft 63 journaled in suitable bearing 64 in the bottom of crank case 35 and connected by pinion 65 to the gear wheel 48, pinion 65 being of the same diameter as pinion 50. The cranks 61, 62 are connected by 50 links 66, 67, respectively, with the guide-ways 56, 57 so as to oscillate said guide-ways with uniform pressure.

In Fig. 1 of the drawing the pinions 50, 55 65 and the gear wheel 48 have been marked with numbers corresponding with the four quarters of a complete revolution of the crank shaft, the pinions which make one revolution to one revolution of the crank shaft being numbered I to IV, and the gear wheel 48 which makes a half revolution to each complete revolution of the crank shaft is numbered throughout the first half I to 60 IV and throughout the second half with the same numbers, but each having the exponent

"a", so that the plain numbers on the gear represent the inspiration and compression strokes, and the numbers with the exponents, the firing and the exhaust strokes. I will now describe the operation, having reference 70 to these numbers.

Assuming the parts to be in the position shown in Figs. 1 and 2, which illustrate them in the firing or working stroke, when the crank reaches the limit of the firing 75 stroke the gear 48 will have turned one-eighth of a turn, and the lower pinion 65 a quarter turn all in the direction of the arrows placed thereon respectively, and the lower main exhaust 13 will be uncovered, letting 80 out the bulk of the exhaust while the cylinder 1 will be moved upwardly only a trifling distance by the combined upward movements of the rod 46 and the guide-ways 56, 57, thus allowing both upper ports 11 and 18 85 to remain closed, but during the next quarter turn of the crank the guide-ways 56, 57 are tilted upwardly to the opposite extreme of the position shown in Fig. 1, as is also the rod 46 which in addition to being tilted is 90 also pulled sharply to the left by passing through the next eighth of its travel, thus causing the slides which carry the eccentric 45 to ride up the steep incline of the guide-ways and thereby open the upper exhaust or 95 auxiliary port 12, that is, bring it into register with ports 15, 18, shortly after the piston starts its return or exhaust stroke. While this upward movement of the cylinder 1 is occurring, air is being compressed in 100 chamber 21, as before described, and when in-take passage 11 reaches by-pass 22, this compressed air rushes downwardly into the cylinder 1 through the passage 23 and cools 105 and clears out the remaining products of combustion. The wrist-pin 47 in moving from the point III to the point IV pulls the eccentric 45 farther outward along the guide-way 56, 57, but the cylinder 1 is not thereby raised any appreciable extent because the 110 guide-way and in fact the rod 46 also moves downward while the eccentric is slightly raised or rocked on its pivot 53 and these movements neutralize each other to the extent of holding the auxiliary exhaust passage 116 practically stationary until the piston again starts down and the cranks 5 and 61 and the wrist-pin pass points IV in their revolution. The wrist 47 in traveling through the first half of its most rapid descent from IV to I and crank 61 through the latter half of its most rapid descent or from point IV to point I, while the eccentric 45 is at the outer end of its travel on the guide 56, 57, naturally causes the cylinder 1 120 to be pulled downwardly very rapidly and a great distance in a short space of time, closing the auxiliary exhaust passages 15, 18 and bringing the intake port 11 opposite the in-take connection or port 16 where it re- 125 130

mains until points II on the pinions and II^a on the gear are or are about to be reached when the piston will be at or about the limit of its inspiration stroke, but as the piston 5 finishes its stroke and starts back the in-take 16 is closed by the ascending movement of the cylinder 1 taking place rapidly as a result of the crank 61 passing point II, lifting the guide-ways 56, 57 while the eccentric is 10 near the outer end thereof and is itself rocked upwardly on its pivot 53 by the downward movement of rod 46 from point I^a to II^a. The in-take now being closed, the piston compresses the charge while the wrist 15 travels from point II^a to point IV^a and the crank 61 from point II to point IV, and consequently during the compression stroke, the cylinder 1 remains substantially at rest with the in-take closed because wrist 47 in passing 20 from point II^a to point IV^a pushes the eccentric 45 to the center of the guide-way, that is, to a point opposite the trunnions 59 where the upward oscillation of the guide-way, due to the crank 61 moving from point 25 II to point III, can have no effect. The working or firing stroke begins approximately at point IV on the crank pinion 50 and pinion 65 and at IV^a on the gear 48, and ceases at point II. As the crank 61 moves 30 from point IV to point II, it first lowers the guide-way 56, 57, and then raises it, but this motion has little or no effect on the cylinder 1, because the wrist 47 during this period pushes the eccentric farther toward trunnion 59; which is the center of oscillation of guide 56 and consequently the in-take 11 and auxiliary exhaust remain closed until the point II is reached, the bulk of the exhaust 35 having taken place as the piston passes the lower exhaust port 13. When the piston again starts up, or shortly thereafter, the cylinder 1 is given a sharp upward movement by the combined upward movement of the guide 56, 57, and the wrist 47 in passing 40 from point II to point III, and the movement of the eccentric 45 toward the left, up the steep incline of the guide-way, as before described, thus connecting the exhaust port 12 with the auxiliary exhaust passage 15, 18. 45 From the point III on the cycle is repeated as before explained.

By the described means, it will be seen that while the crank 5 is making substantially one complete revolution during the 50 compression and explosion strokes of the piston, the movable ports 11 and 12 of cylinder 1 are held in lapped relation with the packing 25, and during the next revolution, while the piston is making its exhaust and 55 explosion strokes, that is, is moving inwardly to expel the exhaust through passage 18 and port 12, and moving outwardly to draw in another charge through port 11, the fixed inlet and exhaust ports 15 and 16 are 60 guarded by the port-controlling means or

provisions 19, 20 surrounding the cylinder 1, and engaging the inner face of cylinder 14. It will also be seen that the complete length of travel of the cylinder 1 is substantially the same as twice the throw of the crank 70 or wrist pin 61, and which is substantially equal to the distance between the horizontal plane of passage 18 and the horizontal plane of fixed inlet port 16, since ports 11, 12 are substantially opposite one another and the cylinder 1 travels from a position where port 11 is in register with port 16 to a position where port 12 is in register with passage 18. The pinions 50, 65 being substantially equal in diameter and the cranks 5 and 61 being of greatly different lengths, with the difference in favor of the crank 5, it follows that while these cranks make the same number of revolutions during each cycle, the crank 61 travels a much less distance, 85 and consequently at a much slower rate of speed than the crank 5, and therefore, while the piston 3 is making a stroke twice the length of crank 5, the cylinder 1 does not move at any time a greater distance than 90 twice the throw of the crank 61, which is substantially equal to the distance between the two horizontal planes in which the passage 18 and port 16 are situated respectively.

What I claim is:

1. In an internal combustion engine, the combination of a working reciprocating piston, a crank shaft connected thereto, a fixed cylinder coaxial with the piston and having intake and exhaust ports, two concentric cylindrical elements one of which surrounds the other and one of which is movable axially with relation to the other, said elements being coaxial with said fixed cylinder and surrounded thereby, the movable one of said elements encompassing the piston and a space in which the piston reciprocates and having means for the admission of a charge of fluid to said space and the exhaust of gases therefrom, the said movable one of said elements having sliding coöperative relation with the other for preventing the escape of fluid from said space during the compression and firing strokes of the piston, means for firing the charge in said space, 110 port-controlling means concentric with said movable element and with the inner face of the fixed cylinder and peripherally coöperating therewith for controlling said intake and exhaust ports therein, and means operatively connecting the movable one of said elements and said port-controlling means with the piston for reciprocating them relatively to the piston and to the fixed cylinder and to the other one of said elements. 115

2. In an internal combustion engine the combination of a working reciprocating piston, a crank shaft connected thereto, a fixed cylinder coaxial with the piston and having intake and exhaust ports, two concentric cy- 130

1. Cylindrical elements one of which surrounds the other and one of which is fixed against movement and the other of which is movable axially with relation to the first, said elements being coaxial with said fixed cylinder and surrounded thereby, the movable one of said elements encompassing the piston and a space in which the piston reciprocates and having means for the admission of a charge of fluid to said space and the exhaust of gases therefrom, the said movable one of said elements having sliding co-operative relation with the other for preventing the escape of fluid from said space during the compression and firing strokes of the piston, means for firing a charge in said space between and against the piston and the fixed one of said elements, means connecting the movable one of said elements with the piston for moving it over the said fixed element to close the said space against the escape of fluid therefrom during the said compression and firing strokes of the piston, and then imparting further movement to it relatively to said fixed element for opening said space during the next two strokes of the piston, and reciprocating port-controlling means located around said movable element and co-operating with the inner face of the fixed cylinder and being also operatively connected with the piston for cutting off communication between said space and exhaust port during the second one of the two last said strokes of the piston.
2. An internal combustion engine having in combination a fixed cylinder provided with a port and a fixed head, means arranged within said cylinder for controlling the said port embodying a second cylinder telescoped therewith and movable with relation thereto and having bearing against said head, a piston arranged in said second cylinder, and means operatively connecting the piston with said second cylinder for moving the latter with relation to the first cylinder and thereby controlling said port.
3. An internal combustion engine comprising in combination a cylinder having an inlet port and an exhaust port, a head over which said cylinder slides, adapted to cover and uncover said ports, a piston in said cylinder and means operatively connected with said piston for moving said cylinder with relation to said head.
4. An internal combustion engine comprising in combination a cylinder having an inlet port and an exhaust port, a head fixed with relation to said cylinder and over which the cylinder slides, said head having inlet and exhaust ports adapted to register respectively with said inlet and exhaust ports in the cylinder, a piston in said cylinder, and means operatively connected with said piston for moving said cylinder with relation to said head.
5. An internal combustion engine comprising in combination a cylinder having inlet and exhaust ports, a head fixed with relation to said cylinder and over which the cylinder slides, said head having inlet and exhaust ports adapted to register respectively with said inlet and exhaust ports in the cylinder, a piston in said cylinder, and means operatively connected with said piston for moving said cylinder with relation to said head.
6. An internal combustion engine comprising in combination a movable cylinder having inlet and exhaust ports, a head fixed with relation to said cylinder and over which the latter slides, an outer cylinder inclosing a part of said movable cylinder and having inlet and exhaust ports respectively, adapted to register with the first said inlet and exhaust ports, a piston in said movable cylinder, and means operatively connected with said piston for moving said movable cylinder with relation to said head and outer cylinder for covering and uncovering said inlet and exhaust ports.
7. An internal combustion engine comprising in combination a cylinder provided with a port, a member telescoped with said cylinder for covering and uncovering said port, a piston in said cylinder, a crank connected with said piston, an eccentric connected with said cylinder for moving it relatively to said member, and means operatively connected with said crank for imparting to said eccentric a rocking or rotating movement on its own axis and a bodily curvilinear movement.
8. An internal combustion engine comprising in combination a cylinder having a port and means for opening and closing said port, one of said parts being movable with relation to the other, an eccentric connected with the movable one of said parts, a piston in said cylinder, a crank connected with said piston, a pivoted guide-way on which said eccentric slides, means operatively connected with said crank for oscillating said pivoted guide-way, and means operatively connected with said crank for sliding said eccentric on said guide-way and for imparting to said eccentric a partial rotation on its own axis.
9. An internal combustion engine comprising in combination a cylinder having a port, a member for opening and closing said port, one of said parts being movable with relation to the other, an eccentric connected with the movable one of said parts, a piston in said cylinder, a crank connected to said piston, two pinions, one of which is connected to said crank, and a gear wheel larger than said pinions connecting them together, a pivoted guide-way on which said eccentric slides, a crank operatively connected to the other one of said pinions and to said guide-way, and a crank connected with said gear and to said eccentric.
10. In a four-cycle internal combustion engine the combination of a fixed cylinder having fixed intake and exhaust ports, a reciprocating piston coaxial with said cylinder, a crank shaft connected to the piston, means for respectively controlling said intake and exhaust ports during two strokes of the cycle and preventing fluid egress from the explosion space of the engine during the other two strokes, embodying a recipro-

- ating cylindrical element coaxial with said fixed cylinder and piston and surrounded by the former and surrounding the latter and also surrounding the explosion space of the 5 engine and having means for the admission of the fluid charge thereto and the exhaust of the gases therefrom, reciprocating port-controlling means external to the explosion space and engaging the inner face of the 10 fixed cylinder, a head telescoped with said reciprocating cylindrical element, means operatively connecting the piston with the said reciprocating cylindrical element and reciprocating port-controlling means for 15 moving said reciprocating port-controlling means to intercept communication between the explosion space and the said fixed ports alternately during one revolution of the crank shaft and moving said cylindrical ele- 20 ment in coöperative relation with said head to close the explosion space against the escape of fluid therefrom during both piston strokes of the next revolution of the crank shaft, and means for firing a charge 25 in the explosion space.
11. In an internal combustion engine the combination of a fixed cylinder having intake and exhaust ports, a reciprocating cylinder surrounded by said fixed cylinder and 30 surrounding the explosion space of the engine and having means for fluid admission to and exhaust from the explosion space, port-controlling means fixed against movement and engaging said reciprocating cylinder for controlling fluid escape therefrom, a working piston reciprocating in and guided by said reciprocating cylinder with relation thereto, means operatively connecting the reciprocating cylinder with the piston for 35 reciprocating the reciprocating cylinder during two successive piston strokes with the said means for fluid admission to and exhaust from the explosion space in lapped relation with said port-controlling means 40 and out of lapped relation therewith during the two succeeding strokes of the piston, and means for firing a charge in the reciprocating cylinder during the second one of the first two said piston strokes.
- 50 12. In an internal combustion engine the combination of a fixed cylinder provided with exhaust and inlet ports, a head fixed to said cylinder and projecting thereinto, and being spaced from the walls thereof, a 55 second cylinder slidable within the first said cylinder and telescoping with said head, a piston working within the second said cylinder, a crank to which said piston is connected, and means operatively connecting 60 the second said cylinder with said crank for opening and closing the said ports.
13. In an internal combustion engine, the combination of a fixed cylinder having fixed intake and exhaust ports, a reciprocating cylinder surrounded by said fixed cylinder and
- surrounding the explosion space of the engine and having ports movable therewith for fluid admission to and exhaust from the explosion space, a cylindrical head fixed against movement and engaging in said reciprocating cylinder for controlling fluid escape therefrom, the working piston reciprocating in said reciprocating cylinder with relation thereto, means operatively connecting the reciprocating cylinder with the piston for reciprocating the reciprocating cylinder during two successive piston strokes with the said ports thereof in lapped relation with said head and out of lapped relation therewith during the two succeeding 80 strokes of the piston, and means for firing a charge in the reciprocating cylinder during the second one of the first two said piston strokes.
14. In an internal combustion engine the combination of a cylinder having a port, a piston, a second cylinder telescoped with the first said cylinder and arranged concentrically with said piston for controlling said port, a fixed head in the first said cylinder 90 and with which head the second said cylinder is telescoped and moves with reference thereto, packing rings interposed between said head and second cylinder, means for igniting a charge between the fixed head and the piston, a crank connected with the piston, and means operatively related to the piston for moving the second said cylinder simultaneously with the piston for controlling said port.
15. In an internal explosion engine, the combination of a fixed cylinder having fixed intake and exhaust ports, an apertured reciprocating cylinder encompassing the explosion space of the engine, telescoped in 105 said fixed cylinder and adapted to place the fixed ports thereof into and out of communication with the explosion space as the reciprocating cylinder moves, a crank shaft, a working piston connected thereto and encompassed by said reciprocating cylinder and reciprocating with relation thereto, means operatively connecting the piston with the reciprocating cylinder for moving the latter to place the explosion space into communication with the intake port of the fixed cylinder during the inspiration outward stroke of the piston and with said exhaust port during the third succeeding piston stroke, said fixed cylinder having a fixed 110 member opposed to the piston at the end of the reciprocating cylinder, and means for exploding the charge between and against said member and piston.
16. In an internal explosion engine, the 125 combination of a fixed cylinder having fixed intake and exhaust ports, an apertured reciprocating cylinder encompassing the explosion space of the engine, telescoped in said fixed cylinder and adapted to place the 130

- fixed ports thereof into and out of communication with the explosion space as the reciprocating cylinder moves, a crank shaft, a working piston connected thereto and encompassed by said reciprocating cylinder and reciprocating with relation thereto, means operatively connecting the piston with the reciprocating cylinder for moving it to place the explosion space into communication with the intake port of the fixed cylinder during the inspiration outward stroke of the piston and with said exhaust port during the third succeeding piston stroke, said fixed cylinder having a fixed member opposed to the piston and encompassed by the reciprocating cylinder, and means for exploding a charge between and against said member and piston.
17. In an internal combustion engine the combination of a fixed cylinder having intake and exhaust ports, a reciprocating cylinder surrounded by said fixed cylinder and surrounding the explosion space of the engine and having ports in its sides adapted to move into and out of register respectively with the ports in the fixed cylinder for admitting fluid to and exhausting fluid from the explosion space, port-controlling means fixed against movement and engaging said reciprocating cylinder for preventing fluid escape through the ports thereof, a working piston reciprocating coaxially with relation to said reciprocating cylinder and surrounded thereby, means operatively connecting the reciprocating cylinder with the piston for reciprocating the reciprocating cylinder with the said ports thereof in lapped relation with said port-controlling means during two successive piston strokes and out of lapped relation therewith during the two succeeding strokes of the piston, and means for firing a charge in the explosion space during the second one of the first two said piston strokes.
18. In an internal combustion engine the combination of a fixed cylinder having intake and exhaust ports, a reciprocating cylinder surrounded by said fixed cylinder and surrounding the explosion space of the engine and having means for fluid admission to and exhaust from the explosion space including an exhaust port movable therewith, port-controlling means internal to said reciprocating cylinder and engaging therewith for controlling said exhaust port thereof, a working piston reciprocating coaxially with relation to said reciprocating cylinder and surrounded thereby, means operatively connecting the reciprocating cylinder with the piston for reciprocating the reciprocating cylinder with the said exhaust port thereof in lapped relation with said port-controlling means during two successive piston strokes and out of lapped relation therewith during the two succeeding strokes of the piston, port-controlling means external to the explosion space and internal to said fixed cylinder and engaging the inner face thereof and movable contemporaneously with the said reciprocating cylinder for intercepting communication between the explosion space and said intake and exhaust ports of the fixed cylinder alternately during the second two said piston strokes, and means for firing a charge in the explosion space during one of the first two said piston strokes.
19. A four-cycle internal combustion engine having in combination a fixed cylinder provided with a closed end fixed with relation thereto, said cylinder having a port, means for controlling said port embodying a movable cylindrical element, a piston arranged concentrically with said movable cylindrical element and opposed to the closed end of said fixed cylinder, means for firing a charge in the space between said fixed end of the cylinder and said piston, and means for moving the said port controlling means to cut off communication between the said space and the said port during one of the inward piston strokes and to place the said port in communication with said space during the next inward piston stroke of the same cycle.
20. In an internal combustion engine, the combination of a fixed cylinder having intake and exhaust ports, a reciprocating cylinder surrounded by said fixed cylinder and surrounding the explosion space of the engine and having means for fluid admission to and exhaust from the explosion space including an exhaust port movable therewith into and out of communication with the exhaust port of the fixed cylinder, port-controlling means internal to said reciprocating cylinder and engaging therewith for controlling fluid escape through the exhaust port thereof, a working piston reciprocating coaxially with relation to said reciprocating cylinder, means connecting the reciprocating cylinder with the piston for reciprocating the reciprocating cylinder with said exhaust port thereof in lapped relation to said port-controlling means during two successive piston strokes and out of lapped relation therewith during the two succeeding strokes of the piston, port-controlling means external to the explosion space and internal to said fixed cylinder and engaging the inner face thereof and movable contemporaneously with the said reciprocating cylinder for intercepting communication between the explosion space and said intake and exhaust ports of the fixed cylinder alternately during the second two said piston strokes, and means for firing a charge in the explosion space during one of the first two said piston strokes.
21. In an internal combustion engine, the combination of a fixed cylinder having intake and exhaust ports, a reciprocating cylinder surrounded by said fixed cylinder and surrounding the explosion space of the engine and having means for fluid admission to and exhaust from the explosion space, a

fixed head containing a water space, telescoped in said reciprocating cylinder and engaging therewith for controlling fluid escape from the explosion space, a working piston 5 reciprocating coaxially with relation to said reciprocating cylinder and surrounded thereby, means operatively connecting the reciprocating cylinder with the piston for reciprocating the reciprocating cylinder with the, 10 said means for fluid admission to and exhaust from the explosion space in lapped relation to said head during two successive piston strokes, and out of lapped relation therewith during the two succeeding strokes 15 of the piston, and means for firing a charge in the explosion space during the second one of the first two said piston strokes.

22. In an internal combustion engine the combination of a fixed cylinder having intake and exhaust ports, a crank shaft, a reciprocating piston connected therewith, a reciprocating cylinder surrounded by the fixed cylinder and surrounding the explosion space of the engine and containing and guiding 25 the piston and in which the piston reciprocates relatively thereto, a cylindrical member telescoped with said reciprocating cylinder and fixed against movement therewith and with the piston, means for exploding 30 a charge in said reciprocating cylinder between and against said member and piston, the wall of said reciprocating cylinder being apertured for induction of the charge and discharge of the exhaust and the apertured area thereof being adapted to move over and away from said member, means 35 connecting the piston with said reciprocating cylinder for reciprocating the reciprocating cylinder with the said apertured area 40 thereof in lapped relation to said member during two successive piston strokes, and means external to said reciprocating cylinder and reciprocable contemporaneously with the movement thereof for controlling fluid admission to the explosion space when the 45 said apertured area is out of lapped relation with the said member during one stroke of the piston, and controlling communication between the fixed exhaust port and explosion 50 space during another stroke of the piston.

23. In an internal combustion engine the combination of a fixed cylinder surrounding the explosion space of the engine and having fixed intake and exhaust ports, a piston, a 55 crank shaft connected thereto, means for firing a charge in said explosion space and means for respectively controlling fluid egress from the explosion space and communication between the explosion space and 60 said fixed ports embodying two cylindrical telescoped elements, one of which encompasses the explosion space and reciprocates contemporaneously with the piston and with relation to the other of said elements, which 65 latter element is fixed against movement,

one of said elements having its wall apertured throughout a portion of its area for fluid admission to and exhaust from the explosion space and both of said elements being concentric with said fixed cylinder, a 70 packing interposed between the contiguous faces of said elements and secured to one of them for covering the said apertured area of the other one during one inward stroke of the piston and the succeeding outward 75 stroke, said packing being substantially equal in width to the travel of said reciprocating element during the two said strokes of the piston, means connecting the piston with the said reciprocating element for moving it until said apertured area and packing are in overlapped relation substantially throughout the revolution of the crank shaft including said two piston strokes and out of such relation substantially throughout the 85 immediately preceding revolution of the crank shaft, the said means for controlling communication between the explosion space and fixed ports also including reciprocating 90 port-controlling means surrounding said reciprocating element and connected with the piston and having sliding co-operative relation with the inner face of said fixed cylinder for alternately cutting the said intake and exhaust ports off from communication 95 with the explosion space during the second said revolution of the crank shaft.

24. In an internal combustion engine the combination of a piston, a crank shaft connected thereto, a fixed cylinder having fixed 100 intake and exhaust ports, a head fixed in said cylinder against movement with the piston, reciprocating port-controlling means embodying a cylindrical element surrounding the piston and telescoped with said head 105 and surrounded by said fixed cylinder and encompassing the explosion space of the engine, said reciprocating port-controlling means having ports co-operating exteriorly with the fixed cylinder to open and close 110 communication between the explosion space and said fixed ports alternately during one revolution of the crank shaft, said cylindrical elements co-operating interiorly with the said head to close egress from the explosion space during the next revolution of the crank shaft, and means for firing a 115 charge in the explosion space during the latter said revolution.

25. In an internal combustion engine, the combination of a piston, a crank shaft connected thereto, two cylindrical telescoped elements, one of which surrounds the explosion space of the engine and is operatively connected with the piston and reciprocates contemporaneously therewith with relation to the other element, and which latter element is fixed against movement with the piston, one of said elements having means for fluid admission to and exhaust 120

- from the explosion space, a packing interposed between the contiguous faces of said elements for covering said means and being equal in width to the travel of said reciprocating element during the compression and explosion stroke of the piston, means for supplying and exhausting the charge and spent gases respectively coöperating with the first said means, and means for firing 10 the charge in the explosion space.
26. In an internal combustion engine, the combination of a fixed cylinder having fixed intake and exhaust ports, a reciprocating cylinder forming the side walls of the explosion space of the engine and having means for fluid induction to and exhaust from the explosion space and being surrounded by said fixed cylinder and adapted to place the fixed ports thereof into and out 15 of communication with the explosion space as the reciprocating cylinder moves, a crank shaft, a working piston connected thereto and embraced by said reciprocating cylinder, and reciprocating directly therein 20 with relation thereto, means operatively connecting the piston with the reciprocating cylinder for reciprocating the latter to place the explosion space into communication with the intake port of the fixed cylinder during 25 the inspiration outward stroke of the piston and with said fixed exhaust port during the third succeeding piston stroke, said fixed cylinder having a fixed head opposed to the piston and filling the end of the reciprocating 30 cylinder and adapted to lap the first said means to prevent egress from the explosion space during the two piston strokes immediately succeeding said inspiration stroke, and means for exploding the charge 35 between and against said head and piston.
27. In an internal combustion engine, the combination of a fixed cylinder having fixed intake and exhaust ports, means for controlling fluid ingress to and egress from the explosion space embodying a cylindrical head fixed against movement with relation to the said fixed cylinder, and projecting thereinto and spaced from the walls thereof, and a reciprocating cylinder surrounded by 40 said fixed cylinder and surrounding the explosion space of the engine and having means for fluid induction to and exhaust from the explosion space, said reciprocating cylinder being telescoped over said head
- whereby the explosion space is opened and closed as the reciprocating cylinder moves, port-controlling means around said reciprocating cylinder engaging and coöperating with the inner face of the fixed cylinder for controlling said fixed ports therein, a working piston reciprocating in said reciprocating cylinder with relation thereto, a crank shaft connected to said piston, means operatively connected with the piston for moving the reciprocating cylinder and said port-controlling means with relation to the said head and fixed cylinder in concert with the movement of the piston for opening communication between the explosion space and the said fixed intake port during an outward piston stroke, then lapping said means for fluid induction and exhaust of the reciprocating cylinder over the said head to close the explosion space during the two succeeding piston strokes, and finally opening communication between the explosion space and said fixed exhaust port during the piston stroke immediately following said two succeeding strokes, and means for exploding a charge between said head and piston.
28. In an internal combustion engine, the combination of a fixed cylinder having intake and exhaust ports, a cylindrical head projecting into said cylinder and spaced from the walls thereof and forming an annular space therewith, two concentric cylindrical elements telescoped in said cylinder over said head, around the explosion space of the engine, reciprocably fitted in said annular space, the inner one of said elements having ports adapted to communicate with the said intake and exhaust ports; and engaging the exterior of said head for controlling said ports therein, and the outer one of said elements engaging the interior face of the fixed cylinder for controlling the said ports therein, a working piston reciprocating axially with relation to said elements and surrounded by the inner one thereof, speed reducing means positively connecting the piston with said elements for reciprocating them with relation to the said head and fixed cylinder, and means for firing a charge in the explosion space.
